No. 896,500.

PATENTED AUG. 18, 1908.

W. E. WOLFE & G. H. PEDDLE.
FENCE POST.
APPLICATION FILED FEB. 4, 1908.

UNITED STATES PATENT OFFICE.

WILLIAM E. WOLFE AND GEORGE H. PEDDLE, OF PERRY, NEW YORK.

FENCE-POST.

No. 896,500.

Specification of Letters Patent.

Patented Aug. 18, 1908.

Application filed February 4, 1908. Serial No. 414,845.

To all whom it may concern:

Be it known that we, WILLIAM E. WOLFE and GEORGE H. PEDDLE, citizens of the United States, residing at Perry, in the 5 county of Wyoming and State of New York, have invented certain new and useful Improvements in Fence-Posts, of which the following is a specification.

The purpose of this invention is the 10 provision of a portable fence post which involves a simple construction and is practically indestructible, the post being of such formation as to be taken apart and set up so as to economize space in storing or transportation and 15 to facilitate handling.

For a full understanding of the invention and the merits thereof and also to acquire a knowledge of the details of construction and the means for effecting the result, reference is 20 to be had to the following description and accompanying drawings.

While the invention may be adapted to different forms and conditions by changes in the structure and minor details without departing from the spirit or essential features 25 thereof, still the preferred embodiment is shown in the accompanying drawings, in which:

Figure 1 is a perspective view of a fence 30 post embodying the invention. Fig. 2 is a side view of the lower portion of the post with the base in section. Fig. 3 is a detail perspective view of a portion of the post, the upper end of the brace and the connecting 35 key, said parts being separated. Fig. 4 is a sectional view of the base and the lower portion of the post and brace, the full lines showing the position of the post and brace when 40 about to place the same in position or remove them from the base, and the dotted lines showing the position of the said parts when 45 properly positioned. Fig. 5 is a detail perspective view on a larger scale of the joint formed between the post and brace.

Corresponding and like parts are referred to in the following description and indicated in all the views of the drawings by the same reference characters.

The post comprises angularly disposed 50 wings 1 and 2. The wings 1 constitute the front or outer portion of the post and is formed with corrugations or transverse grooves 3 in which the fence or runner wires 55 are seated, thereby preventing vertical displacement thereof. The rear wing 2 strengthens the post and provides attaching

means for the upper end of the brace 5 and a lower shoulder to limit the downward movement of the post when placed in position upon the base 6.

In the preferable construction, the post consists of an angle iron or strip bent upon itself intermediate of its longitudinal edges to form the wings 1 and 2. The front or outer portion 1 projects below the rear wing 2 and is curved forwardly to provide an extension 7 for securing the foot of the post to the base 6. The lower end of the rear wing 2 forms a shoulder or stop which engages with the upper side of the base 6 and limits the downward movement of the post. To admit of adjusting the post so as to plumb the same irrespective of the inclination of the base, the lower end of the rear wing 2 is curved slightly and cut away at its rear corner, as shown at 8. A vertical or longitudinal slot 9 is formed in the rear wing 2 and is widened at intervals in its length, as indicated at 10, the purpose being to admit of adjustably connecting the brace 5 with the post and to receive the key 50 by means of which the connection is made.

The brace 5 is of angle form in transverse or horizontal section and is provided at its lower end with a curved extension 11 corresponding to the extension 7 at the lower end 35 of the post and for a like purpose. The curved extension 11 is formed at the lower end of the outer wing of the brace, the lower end of the inner wing being constructed in a similar manner to the lower end of the rear 40 wing 2 of the post and for a like purpose, namely, to limit the downward movement of the brace and to provide for limited adjustment thereof when plumbing the post. A key hole slot 12 is formed in the upper portion 45 of the inner wing of the brace and is adapted to register with the vertical or longitudinal slot 9 of the post and to receive the interlocking end of the key connecting the brace with the post. A slot 13 is provided 50 in the upper end of the outer wing of the brace to receive the rear wing 2 of the post, and thereby prevent relative lateral displacement of the post and brace.

The key for connecting the brace and post 55 comprises a handle 14 having a bent end 15 and a nib 16 projected laterally from the extremity of the bent end 15. The nib 16 and adjacent portion of the bent end 15 forms a head which is adapted to pass through the key hole slot 12 and the slot 9 when the parts 5 and 3 are adjusted to cause said slots to

register. After the brace has been adjusted to bring the key hole slot 12 in position with a portion of the slot 9, the key is placed so that its head will pass through the registering slots, after which the key is given a one-quarter turn to cause the handle 14 to occupy a pendent position, and the nib 16 of the head to sit cross wise of the registering slots and secure the parts, which are confined between the handle 14 upon one side and the nib 16 upon the opposite side. The bent end 15 corresponds to the enlarged portions of the slots 9 and 12, whereas the nib 16 is of a size to pass through the contracted portions of said slots.

The base 6 is of concrete and oblong in form and is provided near each end with an opening to receive the extension of the post and brace by means of which each is anchored, respectively, to the base. A wire or rod 17 embedded in the base and extending transversely thereof, is engaged by the curved anchoring extension of the post and brace, and thereby preventing the same from breaking through the base when subjected to strain or a blow or jar. The base may be strengthened and reinforced longitudinally by other wires, rods or bars 18 and the same may overlap the transverse wires or rods 17 to further fix the position of the latter. The lower side of the base is grooved longitudinally to admit of the base obtaining a secure footing upon the ground or surface upon which it may be placed.

When the key is removed, the brace and post may be readily disconnected from the base by moving their upper ends outward. When the post and brace are in position, their respective extensions 7 and 11 pass through the openings 19 near the ends of the post and engage under the transverse wires or rods 17, and after the post has been plumbed the brace is connected thereto by passing the head of the key through the registering slots in the manner specified, the key being secured by giving the same a one-quarter turn.

The fence or runner wires 4 are secured to the post by means of clips 20, which are of U-form and have the ends of the side members bent to provide hooks so as to engage over the wires at each side of the post. The wires are prevented from vertical movement by being seated in selected corrugations or transverse grooves 3. To prevent longitudinal movement of the fence wires, the latter are slightly crimped or off-set at the sides of the post, and to effect this result a tool 21 is employed, the same consisting of a handle and a fork, the prongs of the latter terminating in hooks which are adapted to engage over the fence wire at the sides of the post, as indicated most clearly in Fig. 1. A fulcrum 22 of the tool is adapted to engage with the post so that upon depressing the outer end of

the handle of the tool the fork members are moved so as to deflect the wire at the sides of the post and enable a clip 20 to be placed in position.

Having thus described the invention, what is claimed as new is:

1. In a fence post, the combination of a base having an opening, a post having a shoulder near its lower end to rest upon the base and limit the downward movement thereof and form a support therefor, and having a curved extension to pass through said opening of the base and engage with the underside thereof when moving the upper end of the post from an inclined to a vertical position, thereby preventing vertical displacement of the post.

2. In a fence post, the combination of a base having an opening, and a post comprising angularly disposed wings, the lower end of one of the wings forming a stop to engage with the upper side of the base and support the post and limit the downward movement thereof, and the other wing having a curved extension projected below the extremity of the first mentioned wing to pass through the opening of the base and engage with the lower side thereof and secure the post against vertical displacement.

3. In a fence post, the combination of a base having an opening, a fence post comprising angularly disposed wings, one of which wings forms a stop to engage with the upper side of the base to support the post and limit its downward movement, and the other wing having a curved extension to pass through the opening of the base and engage with the underside thereof, and a brace secured at its lower end to said base and having its upper end adjustably connected with the rear wing of the post.

4. In a fence post, the combination of a base, a post secured at its lower end to the base and comprising a rear wing in which is formed a vertical or longitudinal slot and which slot is widened at intervals in its length, a brace connected at its lower end to the base and having a key hole slot at its upper end to register with the slot in the rear wing of the post, and a key for adjustably connecting the brace to the post, said key having a head to pass through the registering slots of the brace and post and adapted to turn to interlock and secure said parts.

5. In a fence post, the combination of a base, a post secured at its lower end to the base and comprising a rear wing in which is formed a vertical or longitudinal slot and which slot is widened at intervals in its length, a brace connected at its lower end to the base and having a key hole slot at its upper end to register with the slot in the rear wing of the post, and a key comprising a handle having a bent end provided with a lateral nib, said nib and the adjacent portion

of the bent end forming a head, and which head is adapted to pass through the registering slots of the brace and post, the parts of the latter being confined between the handle 5 and nib of the key after the latter has been given a partial turn.

6. In a fence post, a base of concrete having openings near each end and having reinforcements embedded therein with portions 10 adjacent to the said openings, a post having a curved extension at its lower end to pass through an opening of the base and engage under a part of the reinforcement adjacent to said opening, a brace having a curved ex- 15 tension at its lower end to pass through the other opening of the base and engage under a

part of the reinforcement adjacent to said opening, and means for adjustably connecting the upper end of the brace to the post.

In testimony whereof we affix our signatures in presence of two witnesses.

WILLIAM E. WOLFE. [L. s.]
GEORGE H. PEDDLE. [L. s.]

Witnesses as to the signature of William E. Wolfe:
